US00D657865S

(12) **United States Design Patent**
Williams

(10) **Patent No.:** **US D657,865 S**
(45) **Date of Patent:** **** Apr. 17, 2012**

(54) **CARTRIDGE FOR SURGICAL FLUID MANAGEMENT SYSTEM**

(75) Inventor: **Jeffrey B. Williams**, Hudson, OH (US)

(73) Assignee: **Thermedx, LLC**, Solon, OH (US)

(**) Term: **14 Years**

(21) Appl. No.: **29/357,184**

(22) Filed: **Mar. 8, 2010**

(51) **LOC (9) Cl.** **24-02**

(52) **U.S. Cl.** **D24/111**

(58) **Field of Classification Search** **D24/107, D24/108, 11, 169, 231, 232; 604/29, 30, 604/34, 113, 114, 151, 153; 417/32, 474, 417/477.2**

CLAIM

The ornamental design for a cartridge for surgical fluid management system, as shown and described.

DESCRIPTION

FIG. 1 is a perspective view of a cartridge for surgical fluid management system;

FIG. 2 is a front elevation view of the cartridge of FIG. 1;

FIG. 3 is a rear elevation view of the cartridge of FIG. 1;

FIG. 4 is a plan view of the cartridge of FIG. 1;

FIG. 5 is a bottom view of the cartridge of FIG. 1;

FIG. 6 is a right elevation view of the cartridge of FIG. 1; and,

FIG. 7 is a left elevation view of the cartridge of FIG. 1.

The broken lines showing environmental structure are for

illustrative purposes only and form no part of the claimed

design.
